UNITED STATES PATENT OFFICE.

WILLARD F. RICHARDS, OF BUFFALO, NEW YORK.

MOLDING-MACHINE.

SPECIFICATION forming part of Letters Patent No. 532,213, dated January 8, 1895.

Application filed January 8, 1894. Serial No. 496,037. (No model.)

To all whom it may concern:

Be it known that I, WILLARD F. RICHARDS, a citizen of the United States, residing at Buffalo, in the county of Erie and State of New York, have invented new and useful Improvements in Molding-Machines, of which the following is a specification.

This invention has reference to molding machines of that class which contain an abutment or stationary ramming block, a table or support for the flask to be rammed, arranged underneath the said block and a follower whereby the flask is moved toward the block for ramming the sand in the same.

15 My invention relates more particularly to machines of this kind in which the flask support consists of a rotary table, whereby a number of flasks may be successively brought under the ramming block.

20 In the accompanying drawings, consisting of two sheets:—Figure 1 is a sectional elevation of my improved molding machine, showing the followers in their normal positions. Fig. 2 is a horizontal section of the machine

25 in line 2—2, Fig. 1. Fig. 3 is a sectional elevation of the machine, the section being taken at right angles to Fig. 1, and one of the followers being lowered to the position in which the pattern is stripped from the flask. Fig.

30 4 is a vertical longitudinal section, on an enlarged scale, of the outer position of one of the slides and adjacent parts. Fig. 5 is a cross section in line 5—5, Fig. 4.

Like letters of reference refer to like parts in the several figures.

A is the stationary bed or base of the machine, and A' A² are two upright rods or standards secured at their lower ends to the bed and connected at their upper ends by a

40 cross piece A³. B is the horizontal flask-supporting table arranged to turn on the rod A' and consisting of a number of upright, rectangular chambers or casings B', preferably four, as shown.

45 These chambers are carried by a central hub or sleeve B² journaled on a fixed column C which surrounds the rod A'. The hub B² is preferably supported upon the base of this column by a ball bearing d.

50 A horizontal follower E is arranged to move vertically in each of the chambers B' and is provided on its under side with a depending

actuating rod e. Each chamber B' is open at its upper end and provided in its lower end with an opening for the passage of the follower. The follower of each chamber is guided on upright bars or rails g, arranged in the corners of the chamber and fitting into angular guides g' extending downward from the four corners of the follower, as shown in Fig. 2.

H represents open rectangular supporting plates or frames resting upon pins h projecting above the upper edges of the chambers and i are the usual stripping plates secured to the upper sides of said supporting plates.

J is one of the patterns which is secured to the upper side of the follower by any suitable fastening, and K is a half flask resting upon the stripping plate i and secured to the latter by any ordinary means. The stripping plates have the usual openings conforming to the contour of the patterns, through which the latter project into the flask.

L represents the abutment or stationary ramming block secured to the under side of the cross piece A³ and arranged directly over the circular path traversed by the chambers B', so that the several flask-supports may be successively brought under the ramming block by turning the rotary table B.

M represents an upright actuating cylinder arranged below the table B. m is the piston arranged in this cylinder and m' its piston rod which passes upward through the stuffing box of the cylinder and has its upper end located in the circular path of travel of the rods of the several followers E, so that the lower end of any one of the follower rods may be brought directly opposite or in line with the upper end of said piston rod, as shown in Fig. 1, in which position the upward movement of the piston rod is imparted to the follower rod standing above it. The piston of the actuating cylinder may be operated by steam or compressed air which is delivered to the cylinder by a pipe n.

Each follower E is provided with a pair of bell crank levers o for retarding its descent in withdrawing the pattern from the mold. These bell crank levers are mounted on horizontal pivots secured to a fixed upright plate p arranged within the chamber of the follower. The upper arms of these bell crank

levers bear loosely against the under side of the follower and are preferably provided at their ends with bearing rollers for reducing the friction. The lower vertical arms of the 5 levers are connected by links q with a cross head Q which moves in radial guides q^2 arranged within the chamber B' , below the follower.

R represents radial slides arranged between 10 the guides q^2 and bearing loosely with their rear ends against the inner ends of radial adjusting screws or bolts q^3 arranged in the cross head Q , so that the movement of the slide is imparted to the cross head and vice 15 versa. The inner ends of the several slides R pass through openings formed in the adjacent walls of the chambers B' and are provided with anti-friction rollers r which bear against the face of a stationary horizontal 20 cam S secured to the column C, the adjacent portion of the hub of the rotary table being recessed or cut away to clear this cam. The slides R are each provided with a longitudinal slot r' for the passage of the follower rods.

25 The wide, concentric portion of the cam S is made of such a radius that when a slide R bears against such wide portion, the slide is in its outermost position, and the upper arms of the bell crank levers connected with said 30 slide, stand in a substantially horizontal position so as to support the follower resting thereon, in the normal position shown in Fig. 1. The narrow portion of the cam is made of such a radius that when a slide 35 rides over the same, it is allowed to move inwardly under the weight of the follower exerted on the slide through the bell crank levers and the cross head Q thereby permitting the follower to descend sufficiently 40 to withdraw the pattern from the mold. The narrow portion of the cam is preferably arranged toward the rear side of the machine, as shown, so that the followers are allowed to descend to the position for stripping the pattern on that side of the machine only.

45 The rotary table is locked in place, after bringing one of the followers under the ramming block, by any suitable means. A spring catch operated by a treadle T is preferably 50 employed for this purpose.

In the operation of the machine, when the 55 rotary table is turned so that one of the followers E stands under the ramming block the slide R co-operating with said follower is in its outermost position and the follower is sustained in the position shown in Fig. 1, being nearly flush with the upper edge of its chamber. The pattern secured to the follower projects through the opening in the 60 stripping plate and the supporting plate of the latter and the half flask rests upon the stripping plate, having been previously filled with sand, in the usual manner. Upon admitting steam to the actuating cylinder, the 65 piston in the latter rises and strikes the lower end of the follower rod, moving the follower, together with the superposed supporting

frame, the stripping plate and the flask, toward the ramming block, thereby forcing the sand in the flask against the ramming block 70 and packing it around the pattern. Upon now allowing the steam to exhaust from the actuating cylinder, the follower with the superposed parts descends, to the position shown in Fig. 1, when its further descent is prevented by the upper arms of the elbow levers o. In this position of the parts, the frame which supports the stripping plate and half flask rests upon the pins h. The rotary table is now unlocked and given a quarter turn in 75 the direction of the arrow in Fig. 2, so as to bring the partially lowered follower on the rear side of the machine and the next follower under the ramming block. This quarter turn of the table brings the slide of said 80 follower opposite the narrow portion of the cam S, allowing the latter to move inward and the follower with the pattern attached thereto to descend to its lowermost position as shown in the right hand portion of Fig. 3, thereby 85 withdrawing the pattern from the flask and completing the half mold. The depressed follower remains in this position until the rotary table is again shifted for presenting another unrammed flask to the ramming 90 block, when it is again raised to its normal position by its slide riding over the wide portion of the cam S and swinging the bell crank levers into the position shown in Fig. 1. The flasks on the several followers are in this manner 95 successively presented to the ramming block and rammed, and are then moved aside 100 for withdrawing the pattern from the mold.

It is obvious that each follower may be provided with a single bell crank lever o, but a 105 pair of such levers is preferably employed with each follower, as shown, to equalize the strain.

If desired, the outer ends of the slides R may bear directly against the cross heads Q, 110 but the latter are preferably provided with the adjustable bearing screws q^3 . By this construction, any wear of the pivots of the links and bell crank levers can be readily taken up by adjusting the screws q^3 in the 115 cross head Q, thus maintaining the desired relative position of the parts.

By the employment of the follower-retarding devices herein shown and described, the sudden and forcible descent of the followers 120 is prevented and breakage of the mold is obviated, and the movements of the followers required for stripping the patterns from the flasks and again raising the followers to receive a new flask, are performed in the act of 125 turning the rotary table, thus simplifying the operation of the machine.

I claim as my invention—

1. In a molding machine, the combination 130 with the stationary frame, a ramming block and a rotary horizontal table arranged underneath the ramming block, of a follower carried by said table and movable toward and from said block, means for actuating the fol-

lower, a fixed cam having its face arranged eccentrically to the pivot of the rotary table, and a retarding lever carried by said table and having one of its arms arranged to engage 5 with said follower and having its other arm controlled by said cam in all positions of the rotary table, whereby the lever and cam retard the descent of the follower upon moving the latter from under the ramming block and 10 raise the follower to its normal position upon moving it under the ramming block, substantially as set forth.

2. In a molding machine, the combination 15 with the stationary frame and a ramming block, of a rotary table, a follower supported on said table and capable of moving toward and from said block, means for actuating the follower, a bell crank lever bearing with one arm against the follower, a stationary cam, 20 and a slide operated by said cam and connected with the other arm of the bell crank lever, substantially as set forth.

3. In a molding machine, the combination 25 with the stationary frame and a ramming block, of a rotary table, a follower supported on said table and capable of moving toward and from said block, means for actuating the

follower, a bell crank lever bearing loosely with its upper end against the rear side of the follower, a stationary cam, a slide moving in 30 radial ways secured to said table and engaging against said cam and a link connecting the lower arm of the bell crank lever with said slide, substantially as set forth.

4. In a molding machine, the combination 35 with the stationary frame and a ramming block, of a rotary table, a follower supported on said table and capable of moving toward and from said block, a bell crank lever bearing with one arm against said follower, a stationary cam, a radially movable cross head 40 guided in ways on said table and having an adjustable bearing screw, a link connecting said cross head with the other arm of said bell crank lever, and a radial slide bearing with 45 one end against said cam and with its opposite end against the adjustable screw of said cross head, substantially as set forth.

Witness my hand this 27th day of May, 1893.
